FEED DOG FOR SEWING MACHINES

Elmer T. Coates, St. Louis, Mo., assignor to Angelica Uniform Company, St. Louis, Mo., a corporation of Missouri

Application May 28, 1956, Serial No. 587,589

4 Claims. (Cl. 112—216)

This invention relates in general to sewing machines and, more particularly, to certain new and useful improvements in feed dogs therefor.

In the production of various, one-piece garments, there is a necessity to feed the constituent pieces of fabric to a sewing machine at different rates of speed to obtain the desired characteristics in the finished garment. This is particularly evident in the production of one-piece dresses having what is commonly termed a set-in band or belt, in which construction the belt portion is stitched to blouse and skirt-forming pieces, with the latter being gathered in the area of such securement to provide the desired fullness.

Heretofore, in making garments of this type, operators have had to exercise marked skill in order to continuously feed the waist and/or skirt portions by hand at such speed relative to the rate of automatic feed of the belt or band so as to achieve the necessary gathering during stitching. Thus, heretofore, this operation, generally known as "banding" required exceeding experience and dexterity on the part of the operator.

Therefore, it is a primary object of the present invention to provide a feed dog for sewing machines which is adapted for simultaneous feeding of fabric sections of varying extent to a machine at different rates of speed so that the same may be stitched together with the ends of such sections coinciding.

It is another object of the present invention to provide a feed dog for sewing machines having adjustable elements for engaging the fabric sections to be fed at relatively increased rates for effective gathering.

It is another object of the present invention to provide a feed dog for sewing machines which will assure the stitching of pieces of fabric of different extent along a seam extending from one end to the other of the shorter piece without the exercise of skill on the part of the operator.

It is an additional object of the present invention to provide a feed dog for sewing machines which may be economically manufactured; and which is durable and reliable in usage.

These and other detailed objects are obtained by the structures illustrated in the accompanying drawing, in which—

Figure 1 is a perspective view of a feed dog constructed in accordance with and embodying the present invention illustrating the same in operative relation.

Figure 2 is a top plan view of the feed dog.

Figure 3 is an side view.

Figure 4 is a rearward end view.

Figure 5 is a vertical transverse section taken on the line 5—5 of Figure 4.

Referring now by reference characters to the drawing which illustrates the preferred embodiment of the present invention, A generally designates feed dog for use in a sewing machine, which latter may preferably be of the multiple-needle type, as suggested in Figure 1. Said sew-

2

ing machine is of customary construction and hence, although not all parts are shown herein, should be understood to comprise the standard elements. 1 indicates a needle bar having mounted thereon a pair of needles 2, 2'; there being the usual spring-loaded presser bar 3 carrying a presser foot 4 for cooperating with feed dog A in the delivery of work to the machine; which latter also includes a work support or cloth plate (not shown) to which a slotted throat plate 5 is secured, as by screws, in the recognized manner. Said feed dog A comprises a depending shank 6 having an enlarged opening 7 therein for extension therethrough of a screw for securing feed dog A to a feed bar (not shown) which is in turn operatively engaged to the usual mechanical means for imparting the up and down, reciprocatory movement to feed dog A.

Feed dog A comprises a plurality of main or central feed elements 8 of substantially the same length, in mutual parallel relation, and spaced apart for projection through corresponding slots 9 formed in throat plate 5; said feed elements 8 being each of customary, bar-like construction with its upper surface serrated or of general sawtooth contour for fabric-engaging purposes. On either side of the group of central feed elements 8 is a short, feed member 10, 10' disposed rearwardly of the usual opening 11, 11' formed in throat plate 5 for extension therethrough of needles 2, 2' during operation, for engaging the now stitched work in the area of the seam for assisting in the delivery of same from the machine.

Said feed dog A in its normally rearward portion extends laterally outwardly of feed members 10, 10' to form lugs 12, 12', respectively, each of which is transversely tapped for threadedly receiving a set screw 13, 13', respectively, the forward ends of which are presented for abutment against the confronting, rearward end surfaces of lateral or auxiliary feed elements 14, 14' respectively. Said lateral feed elements 14, 14' are engaged adjacent their rearward ends to the proximate side faces of feed dog A, as by means of screws 15, 15' which pass through drilled, countersunk openings in said elements 14, 14' whereby the latter, upon unlocking of screws 15, 15' are adapted for adjustable, swingable movement within a vertical plane, normal to the plane of central feed elements 8. Each lateral feed element 14, 14' may be rocked independently of the other, although, in practice, they will normally be correspondingly adjusted.

To dispose lateral feed elements 14, 14' in any desired relationship to fixed, feed elements 8, 10, 10', the related retaining screws 15, 15' will be loosened; feed elements 14, 14' then rocked into selected position; the set screw 13, 13' are then threaded forwardly or rearwardly, as requisite, until supported abutment is made with the related, adjusted feed elements 14, 14'; and the screws 15, 15' are tightened, so that by means of the same and set screws 13, 13' lateral feed dogs 14, 14' are reliably and securely maintained in selected position.

Lateral feed elements 14, 14' are of relatively greater length than feed elements 8, 10, 10', extending substantially forwardly thereof for purposes presently appearing.

Feed dog A of the present invention is designed primarily for differential feeding of pieces of fabric and the usage thereof is well exemplified in the banding operation. Therein an ungathered, tape-like, band is stitched to the opposed edge portions of a pair of spaced apart, fabric sections of greater extent than said band, so as to mutually secure the same into a unitary garment. In the manufacture of one piece dresses wherein separate pieces of fabric are utilized for the bodice and skirt portions, with the band constituting the belt or waist portion, feed dogs of the type herein disclosed effect the appropriate, simultaneous feeding of the multiple pieces

of fabric to a sewing machine so that the requisite fullness of the bodice and skirt portions will be provided the finished garment. Thus, said bodice and skirt-forming fabric pieces must be gathered during the seaming operation.

Referring to Figure 1, C and D respectively designate pieces of fabric for respectively forming the skirt and bodice of a one piece dress, while E and F represent bands for providing a faced, set-in belt. Fabric pieces C, D, will perchance have a greater corresponding extent than bands E, F to endow the garment with fullness. It will be seen that bands E, F are directed to the machine by the usual guides 16, and will be fed to needles 2, 2' in the customary manner by the coaction of feed elements 8, 10, 10' and presser foot 4. Fabric sections C, D are directed to the machine, as along guides (not shown), being spaced apart a distance slightly less than the width of bands E, F, and with their opposed edge portions presented sandwichingly between the adjacent edge portions of bands E, F, so that the same are relatively disposed for the development of spaced waist seams S in the completed dress.

Said fabric sections C, D will be fed to the machine by lateral feed elements 14, 14', respectively, which will have been secured in an adjusted, upwardly swung position whereby the same will project above the plane of feed dog elements 8, 10, 10'. In view of the relative length of said lateral feed elements 14, 14' the latter will engage fabric pieces C, D in advance of the engagement of bands E, F by feed elements 8, with the result that rate of feed of fabric sections C, D will be relatively greater than that of bands E, F. Hence, per unit of time, greater portions of fabric pieces C, D will be delivered to needles 2, 2' than of bands E, F, whereby said fabric pieces C, D will be gathered during the feeding and be caused to travel at such rate as to assure that their ends will be coincident with those of bands E, F.

It will thus be seen that lateral feed elements 14, 14', provide a desired range of adjustability so as to accommodate fabric sections C, D of varying thickness, as well as to present a desired range of rate of feed therefor. It will be noted that if feed elements 14, 14' are presented for operation while in co-planar relationship with feed elements 8, 10, 10', the fabric sections C, D would be fed at the same rate as the bands E, F, with the result that the desired gathering would not be accomplished and portions thereof would be left in unsecured relation, that is, the ends thereof would not be brought into coincidence with that of bands E, F. As the lateral elements 14, 14' are rocked into increasingly upward position the rate of feed of fabric sections C, D would be increased.

In view of the foregoing, it is evident that the utilization of the present invention assures the appropriate seaming or stitching of multiple fabric sections in desired relation without the exercise of any particular developed skill on the part of the operator. Prior to this invention, to effect the banding operation, an operator had to be highly skilled, and well trained, since the feeding of the fabric sections could only be done by hand, with a practiced eye alone determining the appropriate

rate of speed to assure the development of the waist seams, with the desired gathering for fullness.

It should be understood that changes and modifications in the formation, construction, arrangement, and combination of the several parts of the feed dog for sewing machines may be made and substituted for these herein shown and described without departing from the nature and principle of my invention.

Having thus described my invention, what I claim and
10 desire to secure by Letters Patent is:

1. In a sewing machine having a feed bar and means
for effecting movement of said feed bar, a feed dog for
differential feeding comprising a body having a depend-
ing shank portion engaged to said feed bar for movement
of the feed dog therewith, a plurality of elongated,
spaced apart, parallel fixed feed elements provided in the
upper portion of said feed dog body, said fixed feed ele-
ments being disposed with their longitudinal axes sub-
stantially parallel to the horizontal, an auxiliary feed
element pivotally mounted on each of the opposite sides
of said feed dog body, laterally outwardly of said fixed
feed elements, for movement with said feed dog body,
said auxiliary feed elements being swingable above and
below the plane of said fixed feed elements, and means
for maintaining said auxiliary feed elements in pre-se-
lected position within their arc of swing.

2. In a sewing machine as described in claim 1 where-
in said fixed feed elements project forwardly from the
feed dog body, said auxiliary feed elements being of
greater length than said fixed feed elements for exten-
sion at their forward ends beyond the forward ends of
said fixed feed elements.

3. In a sewing machine as described in claim 2 where-
in said auxiliary feed elements are swingable within a
plane substantially perpendicular to the plane of said
fixed feed elements.

4. In a sewing machine having a feed bar and means
for effecting movement of said feed bar, a feed dog for
differential feeding comprising a body having a depend-
ing shank portion engaged to said feed bar for move-
ment of the feed dog therewith, a plurality of elongated,
spaced apart, parallel fixed feed elements provided in the
upper portion of said feed dog body, said fixed feed ele-
ments being disposed with their longitudinal axes sub-
stantially parallel to the horizontal, an auxiliary feed
element pivotally mounted on at least one side of said
feed dog body, laterally outwardly of said fixed feed
elements, for movement with said feed dog body, said
auxiliary feed element being swingable above and below
the plane of said fixed feed elements, and means for
maintaining said auxiliary feed element in preselected
position within its arc of swing.
